CARTON

Albert E. Bentham, Baltimore, Md., assignor to
The Baltimore Paper Box Company, Baltimore,
Md., a corporation of Maryland

Application June 12, 1942, Serial No. 446,753

9 Claims. (Cl. 229—23)

This invention relates to improvements in cartons, and especially to cartons made from stiff sheet material such as fiberboard.

The primary object of the invention is to provide an inexpensive carton of simple construction and having sufficient strength or rigidity to safely incase eggs or other fragile articles during transport or storage.

Another object is to supply a carton which may be manufactured with a minimum waste of the fiberboard or sheet material because all elements of the carton are of substantially square or oblong shape.

Another purpose of the invention is to furnish a carton that may be shipped in flat condition and readily set up by inexperienced operators.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a plan view of the carton in knock-down condition, and with the end walls canted.

Fig. 2 is a plan view of the carton partly set up.

Fig. 3 is a top plan view of the completed carton with its cover means in open position.

Fig. 4 is an enlarged end elevation with the cover flaps closed.

Referring to the drawings, 10 designates the main blank which is of oblong shape and provided with parallel score lines 11, 12, 13 and 14, so that the blank may be folded to form a bottom 15, opposite side walls 16 and 17, cover 18, and cover flap 19. An end wall 20, formed of double-wall corrugated board, is provided with score lines 21 along which flaps 22, 23, 24 and 25 may be folded to provide an outwardly extending rim at one end of the carton, as shown in Fig. 4. The flap 22 is secured to one end portion of the wall 16 by any suitable means such as staples 26.

A divider 27 is connected to a bottom reinforcing flap 28 by a fold line 29, and such divider is provided at one edge with a short flap 30 adapted to fold along the line 31. Such flap is secured to the inner surface of the medial portion of the side wall 16 by any suitable means such as staples 32.

Another identical end wall 33 is provided with flaps 34, 35, 36, 37, adapted to fold along lines 38 so as to form an outwardly extending rim at that end of the box. The flap 34 is secured to the inner

surface at one end of the side wall 17 by staples 39 or the like.

A second divider 40 is integral with a bottom reinforcing flap 41 adapted to fold on the line 42, and divider 40 also has a short flap 43, foldable on the line 44 and secured to the inner surface of the medial portion of the wall 17 by staples 45 or similar fastening means.

In setting up the carton, while the main blank 10 is lying flat or horizontally, the divider 27 and the end wall 20 are bent upwardly at right angles to the wall 16, and the bottom flap 28 is bent at right angles to the wall 27, as indicated in Fig. 2. Then the end wall 33, divider 40 and bottom reinforcing flap 41 are set up in the same manner, with reference to the wall 17, as indicated in such figure. Then the side walls are bent toward one another so as to superpose the bottom reinforcing flaps 28 and 41 on the bottom 15, and the assemblage is completed by securing the dividers together by staples 46. As this will hold the carton in set-up condition, flaps 24 and 25 of the end wall 20 can be secured respectively to the side walls 17 and bottom 15 by staples 47 or the like. Afterwards, the flaps 35 and 36 of the end wall 33 can be stapled respectively to the bottom 15 and side walls 16. At this time, the cover elements 18 and 19 are in position at the top of the carton, and after the carton has been filled, they can be secured to the flaps 23 and 37 of the end walls by staples 48 or the like, to complete the carton for shipment or transport.

If desired, hand holes 49 may be cut in the end walls so that they will be in position adjacent the top of the carton.

From the foregoing it is believed that the construction and advantages of the improved carton may be readily understood, and I am aware that changes may be made in the details disclosed, without departing from the spirit of the invention, as expressed in the following claims.

What I claim and desire to secure by Letters Patent is:

1. A carton formed of sheet material and comprising an integral one-piece bottom, opposite side walls, and cover means, end walls, each end wall having an outwardly projecting rim, portions of said rims being secured to the inner surfaces of the ends of the side walls and bottom, dividers extending across the carton and secured respectively to the inner surfaces of intermediate portions of the side walls, means securing the dividers together, each divider being integral with a reinforcing flap superposed on the bottom of the carton, each of said reinforcing flaps being of the

same width as the carton and extending from the dividers to an end of the carton, whereby said reinforcing flaps form together an entire second bottom of the carton.

2. A carton formed of sheet material and comprising an integral one-piece bottom, opposite side walls, and cover means, end walls, each end wall having an outwardly projecting rim, portions of said rims being secured to the inner surfaces of the ends of the side walls and bottom, dividers extending across the carton and having flaps secured respectively to the inner surfaces of intermediate portions of the side walls, means securing the dividers together, each divider being integral with a reinforcing flap superposed on the bottom of the carton, each of said reinforcing flaps being of the same width as the carton and extending from the dividers to an end of the carton, whereby said reinforcing flaps together form an entire second bottom of the carton.

3. A carton formed of sheet material and comprising an integral one-piece bottom, opposite side walls, and cover means, end walls, each end wall having an outwardly projecting rim, portions of said rims being secured to the inner surfaces of the ends of the side walls and bottom, dividers extending across the carton and secured respectively to the inner surfaces of intermediate portions of the side walls, means securing the dividers together, each divider being integral with a reinforcing flap superposed on the bottom of the carton, said reinforcing flaps extending in opposite directions away from the dividers, each of said reinforcing flaps being of the same width as the carton and extending from the dividers to an end of the carton, whereby said reinforcing flaps together form an entire second bottom of the carton.

4. A carton formed of fiberboard and comprising five elements, the first element consisting of a rectangular piece folded to form a one-piece bottom, opposite side walls, and closure means, the second and third elements each consisting of a single piece provided with flaps, some of which are connected respectively to the inner surfaces of the bottom and side walls at an end of the carton, each of the fourth and fifth elements consisting of a divider which extends across the carton and has a flap secured to the inner surface of one of the side walls, and another flap resting on and reinforcing the bottom, the last mentioned flaps being of the same width as the carton and together forming an entire second bottom of the carton.

5. A knock-down fibreboard carton ensemble, comprising a rectangular main blank provided with spaced transverse score lines dividing it into a top portion, a side portion, a bottom portion, and another side portion, in the order named, a rectangular end blank having flaps at all edge portions thereof, one of said flaps being secured to one of said portions of the main blank along one edge of the main blank, another similar end blank having one of its flaps secured to one of said portions of the main blank and arranged at the opposite edge of the main blank, a first partition blank extending lengthwise of the main blank and having a flap secured to an intermediate portion of one of the side portions of the main

blank, and a second partition blank extending lengthwise of the main blank, parallel to the first partition blank, and having a flap secured to an intermediate portion of the other side portion of the main blank.

6. A knock-down fibreboard carton ensemble, comprising a rectangular main blank provided with spaced transverse score lines dividing it into a top portion, a side portion, a bottom portion, and another side portion, in the order named, a rectangular end blank having flaps at all edge portions thereof, one of said flaps being secured to one of the side portions of the main blank along one edge of the latter, another identical end blank having one of its flaps secured to the other side portion of the main blank and arranged at the opposite edge of the latter, a first partition blank extending lengthwise of the main blank and having a flap secured to an intermediate portion of one of the side portions of the main blank, and a second partition blank extending lengthwise of the main blank, parallel to the first partition blank, and having a flap secured to an intermediate portion of the other side portion of the main blank, the end blanks and the partition blanks being all arranged at one side of the main blank, and each partition blank having a length substantially equal to two of said portions of the main blank.

7. A carton formed of sheet material and comprising an integral one-piece bottom, opposite side walls, and cover means, end walls, each end wall having an outwardly projecting rim, portions of said rims being secured to the inner surfaces of the ends of the side walls and bottom, dividers extending across the carton and secured respectively to the inner surfaces of intermediate portions of the side walls, each divider being integral with a reinforcing flap superposed on the bottom of the carton, each of said reinforcing flaps being of the same width as the carton and extending from the dividers to an end of the carton, whereby said reinforcing flaps together form a second bottom of the carton.

8. A carton formed of stiff paper material and comprising an integral one-piece bottom, opposite side walls and cover means, end walls united with the side walls and bottom, dividers extending across the carton and secured respectively to the inner surfaces of the intermediate portions of the side walls, each divider being integral with a reinforcing flap superposed on the bottom of the carton and of substantially the same width as the carton, said reinforcing flaps together forming an entire second bottom of the carton.

9. A carton formed of stiff paper material and comprising an integral bottom, opposite side walls and cover means, the bottom being a one-piece element extending from side to side and end to end of the carton, end walls united with the side walls and bottom, dividers extending across the carton and firmly secured respectively to the intermediate portions of the opposite side walls, each divider being united with a reinforcing flap superposed on the bottom of the carton and of substantially the same width as the interior of the carton, said reinforcing flaps together forming an entire second bottom of the carton.

ALBERT E. BENTHAM.
